To all whom it may concern:

Be it known that I, Morris R. Moody, a citizen of the United States of America, residing at Troy, in the county of Miami and State of Ohio, have invented a new, original, and ornamental Design for a Chair or the like, of which the following is a specification, reference being had to the accompanying drawing forming a part thereof.

Fig. 1 is a perspective view of the chair or the like showing my design, the seat and back member being indicated by dotted lines;

The design embodies a chair which has a frame having vertical side supporting members which are connected by inwardly extending interconnecting members to a bottom supporting member which is of a width substantially less than the spacing between said vertical side supporting members.

I claim:
